UNITED STATES PATENT OFFICE.

RAY W. DUMONT, OF NEW YORK, N. Y., ASSIGNOR TO BEST & CO., INC., OF NEW YORK, N. Y., A CORPORATION OF NEW YORK.

DESIGN FOR A DOLL'S HEAD.

Application filed March 30, 1926. Serial No. 17,116. Term of patent 3½ years.

To all whom it may concern:

Be it known that I, RAY W. DUMONT, a citizen of the United States, residing at 244 West 72nd Street, New York city, have invented a new, original, and ornamental Design for Dolls' Heads, of which the following is a specification, reference being had to the accompanying drawing, forming part thereof.

In the drawing:

I claim:

The ornamental design for a doll's head as shown.

RAY W. DUMONT.
